UNITED STATES PATENT OFFICE.

GEORGE H. CARLSON, OF OMAHA, NEBRASKA, ASSIGNOR TO HOESCHEN MANUFACTURING COMPANY, OF OMAHA, NEBRASKA, A CORPORATION OF NEBRASKA.

TOY MACHINE-GUN.

1,306,577.

Specification of Letters Patent. Patented June 10, 1919.

Application filed May 27, 1918. Serial No. 236,951.

To all whom it may concern:

Be it known that I, GEORGE H. CARLSON, a citizen of the United States, and a resident of Omaha, in the county of Douglas 5 and State of Nebraska, have invented certain new and useful Improvements in Toy Machine-Guns, of which the following is a specification.

My invention relates to toy firearms 10 adapted to detonate a series of explosive charges carried by a flexible strip or ribbon, without, however, throwing or discharging any sort of a projectile. It is the object of my invention to provide a toy 15 firearm of the class indicated, imitating in appearance and action the so-called automatic or machine guns used for military purposes.

In the accompanying drawings Figure 1 20 is a side view of gun embodying my invention, Fig. 2 is a partial longitudinal vertical section thereof, Fig. 3 is a longitudinal vertical section looking oppositely from the same plane as in Fig. 2, Fig. 4 is a detail 25 side view of the grip and breech portion of the gun, Fig. 5 is a transverse vertical section on the plane of the line 5—5 of Fig. 4, and Fig. 6 is a detail section on the horizontal and offset line 6—6 of Fig. 3. In 30 Fig. 5 the planes of section of Figs. 2 and 3 are indicated by the broken line and arrows 2—2 and 3—3, respectively.

As above mentioned, the toy gun provided by my invention is intended to imitate 35 a machine-gun, and in pursuance of this object the gun proper is preferably mounted, as shown in Fig. 1, upon a foldable tripod B of which the head has a stem fitting revolvably in a recess 7 in the gun-stock 8 40 at a point near the center of gravity of the gun, so that the latter will balance upon, and may be traversed about, the pivotal support thus formed. The stock 8 may be 45 of wood, and a metal barrel 9 is secured thereto by suitable means such as the screws 10. The principal operating mechanism of the gun is inclosed in a cast metal breech casing formed by similarly shaped right 50 and left side-pieces 11 and 12, of which the front portions fit upon the sides of the stock 8, while the lower and rear portions form a pistol-grip 13. The flanged edges of the two casing parts fit together at a 55 plane intermediate the lateral faces thereof, and the parts are separably secured together

by screws 14 passing through the grip 13, and screws 15 extending transversely through the rear portion of the stock, as shown. The front portion of the casing formed by the parts 11 and 12 is open at the 60 top, and is provided with a sheet-metal cover 16 having portions extending over the sides of the stock 8 and pivotally connected therewith by a transverse bolt 17. The cover may be swung upwardly, as indicated 65 by the arrows *a* in Fig. 4, to expose the working mechanism.

A shaft 18 extends transversely through the central portion of the casing, being journaled in the sides of the parts 11 and 12, 70 and one end of the shaft projecting slightly beyond the latter side-piece. Said projecting end of the shaft is provided with a crank 19 of which the outer end is movable in the circular path indicated by the line *b* 75 in Fig. 4. A latch 20 is pivoted on a screw 21 projecting from the side-piece 12, there being a stop-pin 22 extending through an opening in the latch to limit swinging movement thereof, and a spring 23 being arranged to normally hold the lower end of the latch in the path of the crank 19. The arrangement is such that the latch may swing forward far enough to clear the crank as the same is moved down past it. 80

On the intermediate portion of the shaft 18 there is revolvably mounted a spring-drum comprising a plate 24 and a gear 25 secured in spaced parallel relation to each other by a plurality of posts 26 extending between the 90 outer portions thereof. A spiral main spring 27 is disposed between said plate and gear, the outer end of the spring being connected to one of the posts 26, and the inner end thereof being connected with the shaft. 95 A trigger 28 is pivoted on a stud 29 carried by the casing-part 12, said trigger extending down through an opening in the lower flange of said casing-part. As shown in Fig. 2, the trigger is formed integrally with a sear-piece 30 and is provided with a spring 31 adapted to hold the end of the sear-piece in the path of the posts 26, whereby the same normally prevents rotation of the 100 spring-drum formed by said posts, the plate 24 and gear 25. By turning the crank 19 as indicated in Fig. 4, the main spring 27 may be wound to a suitable tension, retrograde movement of the crank being prevented by engagement thereof with the latch 20, and 110

rotation of the spring-drum being prevented by the sear-piece 30. By pulling the trigger back toward the grip 13, the spring-drum is released so that the same may be driven by 5 the spring. The gear 25 meshes with a pinion 32 secured on a crank-shaft 33 of which the ends are journaled in the casing side-pieces 11 and 12. The crank-portion of said shaft 33 has loosely attached thereto a short 10 connecting-rod 34 which extends upwardly from the crank and has a forked end-portion straddling and pivotally connected with the hammer-bar 35. The latter is pivoted at one end on a shaft 36 extending transversely 15 between the front portions of the side-pieces 11 and 12. The opposite end of the hammer-bar has a head or hammer 37 of which one side is concaved as shown in Fig. 3. Said concaved side of the hammer is adapted 20 for engagement with a cylindrical block 38 which is mounted revolvably on the shaft 18 and is fixedly connected with the gear 25. Adjoining the side of said gear the block is toothed to form a pinion 39 which drives the 25 ammunition-ribbon feed-rollers 40 and 41. Said rollers 40 and 41 are revolvably mounted, respectively, on arms 42 and 43 which are pivoted on the side-piece 11 as shown in Fig. 3. The upper roller 40 carries at one 30 end a pinion 44 which meshes with the pinion 39, so as to be driven thereby, and both of the rollers 40 and 41 are knurled so that the lower roller 41 may be frictionally driven from the upper. A wire spring 45 has the 35 ends thereof engaged with the arms 42 and 43, as shown, said spring serving to press the roller 41 up toward the roller 40, and to press the arm 42 toward the shaft 18, thereby keeping the pinion 44 in mesh with the pinion 39. Adjacent to the feed-rollers 40 and 41 there is an opening in the rearward side 40 of the cover 16, the same having a tongue 46 which extends inwardly from the upper edge of the opening and terminates near the 45 upper roller 40. A sheet-metal guide-trough 47 is secured to the casing-part 11 at the lower edge of the opening and extends into proximity to the lower feed-roller 41, as shown in Fig. 3.

50 The described mechanism is adapted to automatically feed and detonate a series of small charges of explosive material arranged at uniform intervals along a ribbon or strip A of paper or the like. The charge-carrying ribbon is passed through the guide-trough 47 and between the feed-rollers 40 and 41, thence extending forward over the upper side of the block 38, where the explosive charges are struck and detonated by 55 the hammer 37. The used portion of the ribbon, or the fragments and debris therefrom, fall out of the bottom of the casing through an opening provided by the omission of a portion of the casing member 11, 60 and a portion 48 of the lower flange of said

member is extended up vertically so as to terminate near the block 38 and thereby tend to prevent fragments of the ribbon being carried around the block. After fully winding the main spring 27, and starting the end 70 of a strip or roll of the charge-carrying ribbon through the feed-rollers, a large number of the explosive charges may be detonated without interruption, by merely pulling the trigger and holding the same in position to release the drive-gear 25. The explosive charges may also be fired in "bursts" of two or three shots each, by pulling and immediately releasing the trigger, so that the firing mechanism is stopped after the 75 drive-gear has revolved through the angle between two of the posts 26. By turning the crank 19 to wind the main spring simultaneously with the discharging or firing operation, the latter may be continued indefinitely, 80 or as long as the ammunition-ribbon is supplied to the feed mechanism. For practice or drill with the gun, the mechanism may be operated without the use of the ammunition-ribbon, a partial simulation of gun-fire being 85 obtained by the rapid striking of the hammer upon the block 38. From the foregoing it will be seen that my invention provides, by comparatively simple means, a safe and durable toy gun which may be operated so as 90 to closely imitate an actual machine-gun.

Now, having described my invention, what I claim and desire to secure by Letters Patent is:

1. In a toy machine gun, a motor spring, 100 exteriorly winding means therefor located at one side of the gun, an exterior latch projecting into the path of movement of the winding means, trigger mechanism controlling the unwinding thereof, a hammer driven by said motor spring, and ribbon-feeding means actuated by said spring.

2. A toy machine gun comprising the combination with a stock, barrel, grip and trigger mechanism, of ammunition-strip feeding 110 means, a rotary block over which the strip is delivered by the feeding means, a reciprocatory hammer adapted to strike the block at one limit of its travel, and spring actuated means for driving said hammer and feeding 115 means in unison, said driving means being controlled by the trigger mechanism.

3. In a toy machine gun, a breech casing, a motor spring disposed therein, manually actuated means for winding said spring, a rotary element actuated by said spring, a trigger, means controlled thereby for normally preventing rotation of said element, a hammer driven by said rotary element, and a rotary block actuated by the motor spring 120 and arranged to be struck by the hammer at one limit of its movement.

4. In a toy gun, the combination with a barrel, stock, grip, breech casing, and trigger, of a motor spring disposed in the breech 130

- casing, a crank for winding said spring, an exterior latch projecting into the path of movement of the said crank for preventing retrograde movement of the same, a rotary element driven by said spring and controlled by the trigger, and an ammunition-strip feeding device and a striking member driven by said rotary element.
5. In a toy machine gun, a rotary driving member, means for actuating said member, a hammer actuated by said member, ribbon-feeding means actuated by said member and adapted to deliver a ribbon into position to be struck by the hammer, a rotary block arranged to support the ribbon, and a trigger device arranged to normally prevent rotation of said driving member.
10. A toy machine gun including a spring actuated drum, a ribbon supporting block connected with the drum and having gear teeth, feed rollers geared to the said block and actuated by the same for feeding a ribbon to the block, and a hammer actuated by the drum and arranged to strike the ribbon while the same is supported by the rotary block.
15. A toy machine gun including a spring actuated drum, a rotary block connected with the drum at one side thereof, feed rollers geared to and actuated by the block and arranged to feed a ribbon to the block, and means actuated by the drum for striking the ribbon while the same is supported by the rotary block.
20. A toy machine gun including a shaft, a drum mounted on the shaft and having spaced side plates, and connecting transverse members, a spring connected with the shaft and with one of the said transverse members for actuating the drum, a rotary block mounted on the shaft at one side of the drum and connected with the latter and adapted to support a ribbon, and feed rollers actuated by the said block for feeding the ribbon to the said block.
25. A toy machine gun including a shaft, a drum mounted on the shaft and having spaced side plates, and connecting transverse members, a spring connected with the shaft and with one of the said transverse members for actuating the drum, a rotary block mounted on the shaft at one side of the drum and connected with the latter and adapted to support a ribbon, feed rollers actuated by the said block for feeding the ribbon to the said block, and a trigger having a sear arranged to engage the transverse members of the drum for holding the same against rotary movement.
30. A toy machine gun including a shaft, a drum mounted on the shaft and having spaced side plates, and connecting transverse members, a spring connected with the shaft and with one of the said transverse members for actuating the drum, a rotary block mounted on the shaft at one side of the drum and connected with the latter and adapted to support a ribbon, feed rollers actuated by the said block for feeding the ribbon to the said block, and a trigger having a sear arranged to engage the transverse members of the drum for holding the same against rotary movement.

GEORGE H. CARLSON.
